UNITED STATES PATENT OFFICE

2,264,714

LOCOMOTIVE CONTROL SYSTEM

Lynn G. Riley, Pittsburgh, Pa., assignor to Westinghouse Electric & Manufacturing Company, East Pittsburgh, Pa., a corporation of Pennsylvania

Application February 20, 1940, Serial No. 319,879

8 Claims. (Cl. 172—179)

My invention relates, generally, to control systems and, more particularly, to systems for controlling the operation of electric locomotives.

An object of my invention, generally stated, is to provide a control system for electric locomotives which shall be simple and efficient in operation and which may be economically manufactured and installed.

A more specific object of my invention is to provide a system suitable for controlling a locomotive when operating either on alternating current or on direct current.

Another object of my invention is to provide a control system wherein the same master controller may be utilized for controlling a locomotive when operating on either alternating current or direct current.

A further object of my invention is to provide a control system for synchronizing the movements of controllers in two or more locomotives.

Still another object of my invention is to provide a control system for driving a pilot controller at a fixed speed regardless of quick or erratic movements of the master controller.

A still further object of my invention is to prevent skipping of notches during the notching operation.

Other objects of my invention will be explained fully hereinafter or will be apparent to those skilled in the art.

According to the present invention, a buck-boost system of securing a large number of notches, which are a multiple of the number of main transformer taps, is utilized. The buck-boost system may be similar to the one disclosed in Patent No. 2,101,880, issued December 14, 1937, to W. R. Taliaferro and assigned to the Westinghouse Electric & Manufacturing Company. However, in the present system, the operation of the various tap-changing and control switches is controlled by motor-driven control drums instead of by air-operated drums. In addition, the locomotive operates on either alternating current or direct current and the same master controller is utilized for both operations. Also, the equipment is suitable for multiple operation of two or more locomotives and provision is made for synchronizing the pilot controllers during multiple operation.

For a fuller understanding of the nature and objects of the invention, reference may be had to the following detailed description, taken in conjunction with the accompanying drawings, in which:

Figures 1A, 1B and 1C, when combined, con-

stitute a diagrammatic view of a control system embodying my invention;

Fig. 2 is a chart showing the sequence of operation of certain of the control switches when the locomotive is operating on direct current; and

Fig. 3 is a sequence chart for operation on alternating current.

Referring to the drawings, the system shown therein comprises a plurality of motors 10, 11 and 12 having armature windings 13, 14 and 15 and series field windings 16, 17 and 18, respectively, a transformer 19 having a primary winding 21 and a secondary winding 22 for varying the motor voltage when the locomotive is operating on alternating current, and resistors 23 to 30, inclusive, for varying the motor voltage when operating on direct current.

A plurality of main tap switches 1 to 5, inclusive, are provided for changing taps on the secondary winding 22 of the main transformer 19. In order to increase the number of steps obtainable for varying the motor voltage with a relatively small number of taps on the main transformer, an auxiliary buck-boost transformer 31 having a primary winding 32 and a secondary winding 33 is utilized. The secondary winding 33 is connected in the motor circuit as shown and the primary winding 32 may be connected to different taps on the main transformer by means of a plurality of auxiliary tap switches *a*, *b*, *c*, *d* and *e*. A preventive coil 34 is provided in the circuit for the primary winding 32 to permit certain of the auxiliary tap switches to be closed at the same time without short-circuiting a portion of the main transformer 19. The buck-boost system illustrated is of the type described and claimed in the aforementioned Patent No. 2,101,880. However, it will be understood that other buck-boost systems for controlling the motor voltage may be utilized if desired.

In order to vary the motor voltage while operating on direct current, a plurality of switches R1, R2, R3, R4, LR1, LR2, V1, V2, V3 and V4 are provided for changing the resistor connections and shunting the resistors 23 to 30 from the motor circuit. In addition to the foregoing switches, line switches LS1, LS2 and motor switches M1, M5, M9, A1, A4, A5, A8, A9 and A12 are provided for connecting the motors to the power source in the desired relation. A series switch S is also utilized for changing the motors from series to parallel operation. Field shunting switches FS1, FS5 and FS9 are provided for shunting the series field windings 16, 17 and 18,

respectively, in a manner well known in the art.

A changeover switch 35 is provided for connecting a pantograph current collector 36 to the transformer 19 when the locomotive is operating on alternating current, or to the line switches LS1 and LS2 when operating on direct current. A relay 37, having an actuating coil 38 which is connected across a portion of the transformer winding 22, is utilized for interlocking certain of the switches to prevent the incorrect operation thereof. A similar relay 39, having an operating coil 41 which is connected in series with a resistor 42 across the power circuit for the motors when operating on direct current, is also utilized to provide protective interlocking for certain of the switches. It will be seen that the relay 37 is energized when the locomotive is operating on alternating current and the relay 39 is energized when operating on direct current. Therefore, the contact members of these relays may be utilized to insure the correct operation of certain switches which are required for either alternating current or direct current service.

The control energy for operating the control apparatus may be supplied from a battery or other suitable source (not shown) in accordance with a familiar practice. A changeover switch 43 is provided for energizing certain portions of the control equipment when the locomotive is operating on alternating current and other portions of the control equipment when operating on direct current.

A manually operated master controller MC having segments 44, 45 and 46 is disposed for operation by the operator of the locomotive. A pilot controller PC having drum segments 47 and 48 and a plurality of carryover contact segments 49 is located remotely from the master controller MC. Corresponding fingers on the master controller MC and the pilot controller PC are connected by conductors 52 to 68, inclusive, as shown. As will be explained more fully hereinafter, the operation of the controllers is such that the pilot controller is automatically operated to a position which corresponds to any position to which the master controller may be operated.

As shown, the pilot controller is geared to a controller AD having segments 71, 72 and 73 and also to a buck-boost controller BB having a segment 74. The segment 71 of the controller AD is utilized to control the operation of the main tap switches 1 to 5, inclusive, while the locomotive is operating on alternating current. The segments 72 and 73 are utilized to control the resistor shunting switches and certain of the motor connecting switches while operating on direct current. The buck-boost controller BB is utilized to control the operation of the auxiliary tap switches *a* to *e* while operating on alternating current. The ratio of the gears which drive these controllers is such that the buck-boost controller makes two and one-half revolutions for each revolution of the pilot controller PC and the controller AD.

The controllers PC, AD and BB are driven by a pilot motor PM having an armature winding 75 and field windings 76 and 77. The field winding 76 is disposed to cause rotation of the pilot motor in an "on" direction and the field winding 77 causes rotation in an "off" direction. A directional relay DR having actuating coils 78 and 79 is provided for controlling the direction of rotation of the pilot motor PM. The coil 78, when energized, actuates the contact members

of the relay to the position shown in the drawings. When the coil 79 is energized the contact members of the relay are actuated to their other position. The relay is of such a construction that it remains in the position to which it was actuated by the coil last energized until the other coil is energized to operate the relay to the opposite position. In this manner a resistor 80 is connected in the circuit for the armature winding 75 of the pilot motor to produce dynamic braking of the motor when the operating power is removed from the motor circuit.

In order to prevent the control equipment from advancing past a transition point in the event that the proper main tap switches have not closed, a holding relay HR is utilized. The actuating coil of the relay HR is energized through interlocks 81 to 85 provided on the main tap switches 1 to 5, respectively. The relay HR is provided with contact members 86 and 87 which are so connected in the circuit for the pilot motor PM that the motor cannot advance the controllers through a transition point unless the actuating coil of the relay HR is energized during the transition period. The interlocks 81 to 85 are so connected in the circuit for the actuating coil of the relay HR that the relay is not energized unless the proper pair of main tap switches is closed during the transition period. In this manner incorrect operation of the buck-boost switches beyond a transition point is prevented.

In order that the functioning of the foregoing apparatus may be more clearly understood, the operation of the system will now be described in more detail. Assuming that the locomotive is operating on a section of the track in which a trolley conductor 88, which is engaged by the pantograph 36, is energized by alternating current, the transfer switch 35 is actuated to the position which connects the transformer 19 to the pantograph 36. Likewise, the changeover switch 43 is actuated to the position in which a positive conductor 89 of the control source is connected to a conductor 91 which, in turn, is connected to one of the contact fingers engaged by the segment 45 of the master controller MC.

As indicated in the sequence chart in Fig. 3, when the master controller is moved to position 1, the main tap switch 1, the auxiliary tap switches *a* and *b*, and the motor switches A1 and A4 are closed, thereby connecting the motor 10 to the transformer 19. The energizing circuit for the main tap switch 1 may be traced from the positive conductor 89 through conductors 92 and 93, the contact segment 46 of the controller MC, conductor 94, an interlock 95 on the relay 37 which is energized at this time, conductor 96, the segment 71 on the controller AD, conductor 97 and the actuating coil of the switch 1 to negative. The energizing circuit for the auxiliary tap switch *a* may be traced from a positive conductor 98 through an interlock 99 on the relay 37, conductor 101, the segment 74 on the controller BB, conductor 102 and the actuating coil of the switch *a* to negative. The energizing circuit for the switch *b* extends from the segment 74 on the controller BB through conductor 103 and the actuating coil of the switch *b* to negative. The energizing circuit for the motor switch A1 may be traced from the positive conductor 89 through the switch 43, conductor 91, contact segment 45 of the controller MC, conductor 104, an interlock 105 on the relay 37, conductor 106 and the actuating coil of the switch A1 to negative. The ener-

gizing circuit for the switch A4 extends from the previously energized conductor 104 through an interlock 107 on the relay 37, conductor 108 and the actuating coil of the switch A4 to negative.

At this time the motor 10 is connected to the secondary winding 22 of the transformer 19 through the tap switch 1, conductor 109, a portion of the secondary winding 33 of the buck-boost transformer 31, conductors 111 and 112, the switch A1, the series field winding 16, the armature winding 13 and the switch A4 to ground. The buck-boost transformer 31, which is connected to the main transformer at this time through the preventive coil 34 and the switches *a* and *b*, functions to reduce the voltage applied to the motor in the manner described in the aforementioned Patent No. 2,101,880.

When the master controller is moved to position 2, the switches A5 and A8 are closed to connect the motor 11 in the power circuit. The energizing circuit for the switch A5 may be traced from the contact segment 45 through conductor 113, an interlock 114 on the relay 37, conductor 115 and the actuating coil of the switch A5 to negative. The energizing circuit for the switch A8 extends from the conductor 113 through an interlock 116 on the relay 37, conductor 117 and the actuating coil of the switch A8 to negative. At this time the motor 11 is energized through a circuit which extends from the conductor 112 through conductor 118, the switch A5, the series field winding 17, the armature winding 14 and the switch A8 to ground.

When the master controller is actuated to position 3, the switches A9 and A12 are closed to connect the motor 12 in the power circuit. The energizing circuit for the switch A9 extends from the segment 45 through conductor 119, an interlock 121 on the relay 37, conductor 122 and actuating coil of the switch A9 to negative. The energizing circuit for the switch A12 extends from the conductor 119 through an interlock 123 on the relay 37, conductor 124 and the actuating coil of the switch A12 to negative. At this time the motor 12 is energized through a circuit which extends from the conductor 112 through the switch A9, the series field winding 18, the armature winding 15 and the switch A12 to ground.

Also, when the master controller is moved to position 3 the pilot motor PM is energized to rotate the pilot controller PC to position 3. The energizing circuit for the pilot motor may be traced from the conductor 53 which is energized through the segment 46 on the controller MC, the segment 48 on the controller PC, conductors 125 and 126, the contact members 87 on the relay HR, conductor 127, the coil 78 on the directional relay DR, conductor 128, the field winding 76 and the armature winding 75 of the pilot motor and conductor 129 to negative. It will be seen that the pilot controller PC will be stopped on position 3 since the segment 48 moves off of the contact finger to which the conductor 53 is connected, thereby deenergizing the pilot motor.

When the master controller MC is actuated to position 4, thereby energizing the conductor 54, the pilot controller is immediately driven to position 4 by the pilot motor PM. The segment 48 is energized by the conductor 54, thereby energizing the pilot motor through the circuit previously described. When the pilot controller reaches position 4, the segment 48 is deenergized, thereby deenergizing the pilot motor, which is immediately stopped by the dynamic braking circuit which extends from one terminal of the ar-

mature 75 through the "off" field winding 77, a conductor 131, contact members 132 of the relay DR, the resistor 80 and conductor 129 to the other terminal of the armature 75.

It will be noted that the carryover contacts 49 on the pilot controller PC function to prevent the pilot controller from being stopped between positions. The contact segments 49 bridge contact fingers 133 and 134 while the pilot controller is traveling from one position to the next, thereby maintaining an energizing circuit for the pilot motor PM which may be traced from the positive conductor 89 through conductors 92 and 93, the contact fingers 133 and 134 bridged by the segments 49, conductor 135, contact members 136 on the relay DR, the coil 78, conductor 128, the field winding 76, the armature winding 75 and conductor 129 to negative.

As shown by the sequence chart in Fig. 3, when the master controller is on position 4 and likewise the pilot controller is on position 4, the buck-boost controller is also driven to position 4 by the pilot motor. When the buck-boost controller is actuated to position 4, the auxiliary tap switch *a* is deenergized and the auxiliary tap switch *c* is energized, thereby increasing the voltage applied to the motors 10, 11 and 12. The energizing circuit for the switch *c* may be traced from the contact segment 74 on the controller BB through conductor 137 and the actuating coil of the switch *c* to negative.

When the master controller MC is moved to position 5, the pilot controller PC is immediately driven to position 5 by the pilot motor in the manner hereinbefore explained. Likewise, the buck-boost controller BB is actuated to position 5, thereby deenergizing the auxiliary tap switch *b* and energizing the switch *d*. The energizing circuit for the switch *d* extends from the segment 74 through conductor 138 and the actuating coil of switch *d* to negative.

Similarly, when the master controller is moved to position 6, the pilot controller and the buck-boost controller are rotated to position 6 by the pilot motor. This time the switch *c* is deenergized and the switch *e* closed. The energizing circuit for the switch *e* may be traced from the segment 74 through conductor 139 and the actuating coil of the switch *e* to negative.

Also when the master controller is on position 6, the controller AD is driven to position 6 since it is geared to the pilot controller PC. The rotation of the controller AD to position 6 energizes the main tap switch 2 through a circuit which may be traced from the segment 71 through conductor 141 and the actuating coil of the switch 2 to negative.

As explained hereinbefore, the holding relay HR is energized when the switches 1 and 2 are both closed as is the case when the controllers are on position 6 which is a transition point. The energizing circuit for the relay HR may be traced from a positive conductor 142 through the interlock 81 on the switch 1, conductor 143, the interlock 82 on the switch 2, conductor 144 and the actuating coil of the relay HR to negative. The operation of the relay HR opens its contact members 87 and closes its contact members 86, thereby permitting the pilot motor to be energized through a portion 145 of the segment 48 which engages a finger 146 of the pilot controller when it is on position 6. In this manner the pilot motor is energized when the master controller MC is moved to position 7, the circuit for the pilot motor extending from the contact finger 146 through conductors 147 and 148, the contact

members 86 of the relay HR and thence to the pilot motor through the circuit previously traced. Otherwise it would be impossible to energize the pilot motor to drive the pilot controller beyond position 6 since energization of the conductor 125 is prevented by an opening 149 in the segment 48. In this manner advancement of the control equipment beyond a transition point is prevented unless the proper main tap switches are closed during the transition period. It will be seen that similar provision is made for preventing the advancement of the pilot controller during each one of the transition periods, it being necessary for the proper interlocks 81 to 85 on the main tap switches 1 to 5 to be closed during transition to energize the holding relay HR as hereinbefore described.

As the master controller is advanced through the remaining positions the pilot controller PC, the buck-boost controller BB and the controller AD are rotated to the position corresponding to that of the master controller in the manner previously explained. The master controller may be advanced either step-by-step or it may be fully advanced to the last position in one operation. The pilot controller immediately follows the movement of the master controller and is stopped on the position corresponding to that at which the master controller is stopped.

As explained hereinbefore the buck-boost controller BB makes two and one-half revolutions for each revolution of the pilot controller PC and the controller AD. The rotation of the buck-boost controller causes the auxiliary tap switches a to e to be operated in the order shown in the sequence chart in Fig. 3. Likewise, the rotation of the controller AD causes the operation of the main tap switches 1 to 5 as shown in the sequence chart. As the controller AD advances to the proper positions, conductors 151, 152 and 153 are energized to close the main tap switches 3, 4 and 5 at the proper time during the notching operations. In this manner the main tap switches and the auxiliary tap switches cooperate with the buck-boost transformer 31 to increase the voltage applied to the motors in the manner described in the aforementioned Patent 2,101,880.

If it is desired to lower the voltage applied to the traction motors, the master controller MC is moved backward toward the "off" position, thereby causing the pilot motor PM to be reversed which reverses the direction of rotation of the pilot controller PC, the buck-boost controller BB and the controller AD. Assuming, for example, that the master controller is returned to position 10, the conductor 60 is energized to energize the segment 47 on the pilot controller PC which, in turn, energizes the pilot motor through a circuit which extends from the segment 47 through conductor 154, the coil 79 of the directional relay DR, conductor 131, the "off" field 77, the armature 75 of the pilot motor and conductor 129 to negative.

In this manner the pilot motor is reversed and also the directional relay DR is operated to its other position by the energization of the coil 79. When the pilot controller reaches position 10, the segment 47 is deenergized, thereby deenergizing the pilot motor. A dynamic braking circuit is established through the directional relay to ensure the stopping of the pilot motor on the correct position. The dynamic braking circuit may be traced from one terminal of the armature 75 through the field winding 76, conductor 128, contact members 132 of the relay DR which, at this time, is in the opposite position from that

shown, resistor 80 and conductor 129 to the other terminal of the armature 75.

Therefore, it will be seen that the master controller may be operated in either direction and that the pilot controller will immediately follow to the position corresponding to that of the master controller. Furthermore, it will be seen that the equipment herein described is suitable for the multiple operation of locomotives or cars, since any number of pilot controllers and the associated control equipment may be controlled from one master controller by merely duplicating the pilot controller and its associated equipment in each locomotive which is to be controlled from the one master controller.

When the locomotive or vehicle is operated in a section of the track system in which the power conductor 88 is energized from a direct current source, the changeover switch 35 is thrown to its lowermost position in which a conductor 155 is utilized to connect the motors to the pantograph 36, as will be explained more fully herein-after. Likewise, the control changeover switch 43 is thrown to its right-hand position in which a conductor 156 is energized from the control source to energize the segment 44 of the controller MC when this controller is moved to position 1.

As explained hereinbefore, the coil 41 of the interlocking relay 39 is energized when the changeover switch 35 is in position for operation on direct current. The operation of the relay 39 closes its contact members 157, thereby supplying control energy to the segments 72 and 73 of the controller AD when the master controller MC is actuated to position 1. The energizing circuit for the controller AD may be traced from the positive conductor 89 through conductors 92 and 93, the segment 46 on the controller MC, conductor 94, the interlock 157 on the relay 39 and conductor 158 to the segment 72 of the controller AD. As shown, the segment 73 is connected to the segment 72. At this time, the buck-boost controller BB and the segment 71 of the controller AD are deenergized since the interlocking relay 37 is deenergized. Therefore, the rotation of the controller BB and the segment 71 of the controller AD has no effect while the locomotive is operating on direct current.

As shown by the sequence chart in Fig. 2, when the master controller MC is actuated to position 1, the switches LS1, VI, MI, A12 and S are closed to connect the motors to the direct current power source in series-circuit relation. The energizing circuit for the switch LS1 may be traced from the segment 44 on the controller MC through conductor 161 and the actuating coil of the switch LS1 to negative. The energizing circuit for the switch VI may be traced from the segment 72 on the controller AD through conductor 162 and the actuating coil of the switch VI to negative. The energizing circuit for the switch MI extends from the segment 44 on the controller MC through conductor 163 and the actuating coil of the switch MI to negative. The energizing circuit for the switch A12 extends from the segment 44 through conductor 164, an interlock 165 on the relay 39 which is closed at this time, conductor 166 and the actuating coil of the switch A12 to negative. The energizing circuit for the switch S may be traced from the segment 44 on the controller MC through conductor 167, and the actuating coil of the switch S to negative.

At this time the motors 10, 11 and 12 are con-

nected to the power source in series-circuit relation and in series with a portion of the motor accelerating resistors. The circuit for the motors may be traced from the pantograph 36 through the switch 35, conductors 155 and 163, the switch LS1, conductor 169, the resistors 25, 26 and 27, conductor 171, the switch V1, the resistor 23, conductor 172, the switch M1, conductor 173, the series field winding 16 and the armature winding 13 of the motor 10, conductor 174, contact members 175 of the switch S, conductor 176, the armature winding 14 and the series field winding 17 of the motor 11, conductors 177 and 178, contact members 179 of the switch S, conductor 181, the series field winding 18 and armature winding 15 of the motor 12 and the switch A12 to ground.

At this time the field shunting switches FS1, FS5 and FS9 are also closed to shunt the field windings of the motors 10, 11 and 12, respectively, thereby reducing the initial torque developed by the motors to provide a smoother starting of the locomotive. The energizing circuit for the switch FS1 may be traced from the segment 72 on the controller AD through conductor 182 and the actuating coil of the switch FS1 to negative. The energizing circuit for the switch FS5 extends from the segment 72 through conductor 183 and the actuating coil of the switch FS5 to negative. The energizing circuit for the switch FS9 extends from the segment 72 through conductor 184 and the actuating coil of the switch FS9 to negative.

When the master controller is actuated to position 2 the switch S is opened and the switches LS2, V2, M5, M9, A4 and A8 are closed, thereby connecting the motors in parallel-circuit relation. Following the closing of the switch LS2 the switches R1 and R2 are closed to shunt the resistors 25 and 30 from the motor circuit. The energizing circuit for the switch LS2 may be traced from the segment 44 on the controller MC through conductor 185 and the actuating coil of the switch LS2 to negative. The energizing circuit for the switch V2 may be traced from the segment 72 on the controller AD through conductor 186 and interlock 187 on the switch LS2, which has just been closed, and the actuating coil of the switch V2 to negative. The energizing circuit for the switch R1 may be traced from the segment 73 on the controller AD through conductor 188, an interlock 189 on the switch LS2, conductor 191 and the actuating coil of the switch R1 to negative. The energizing circuit for the switch R2 extends from the segment 73 through conductor 192, an interlock 193 on the switch LS2 and the actuating coil of the switch R2 to negative. The energizing circuit for the switch M5 may be traced from the segment 44 on the controller MC through conductor 194 and the actuating coil of the switch M5 to negative. The energizing circuit for the switch M9 extends from the conductor 194 through the actuating coil of the switch M9 to negative. The energizing circuit for the switch A4 may be traced from the segment 44 on the controller MC through conductor 195, an interlock 196 on the relay 39, conductor 108 and the actuating coil of the switch A4 to negative. The energizing circuit for the switch A8 extends from the conductor 195 through an interlock 197 on the relay 39, conductors 198 and 117 and the actuating coil of the switch A8 to negative.

At this time the motors are connected in parallel-circuit relation and certain of the motor

accelerating resistors are also connected in parallel in the motor circuit. The power circuit for the motors may be traced from the conductor 155 through the conductor 168, the switch LS1, conductors 169 and 199, the switch R1, the resistors 26 and 27, conductor 171, the switch V1, and the resistor 23 to the conductor 172, and also from the conductor 168 through the switch LS2, conductors 201 and 202, the switch R2, resistors 29 and 28, conductor 203, the switch V2 and the resistor 24 to the conductor 172, thence through the switch M1, conductor 173, the series field winding 16 and armature winding 13 of the motor 10 and the switch A4 to ground, and also from the conductor 172 through the switch M5, conductor 204, the series field winding 17 and armature winding 14 of the motor 11 and the switch A8 to ground, and also from the conductor 172 through the switch M9, conductor 205, the series field winding 18 and the armature winding 15 of the motor 12 and the switch A12 to ground.

When the master controller MC is actuated to position 3, the pilot controller is rotated to position 3 by the pilot motor in the manner hereinbefore described. The controller AD is also rotated to position 3 since it is geared to the pilot controller.

As shown in the sequence chart in Fig. 2, the field shunting switch FS1 is deenergized on position 3. When the controllers are actuated to position 4 the field shunting switch FS5 is deenergized and on position 5 the field shunting switch FS9 is deenergized. In this manner the shunting circuits are removed from the field windings of the motors step-by-step to apply full field strength to the motors and increase the motor torque.

When the controllers are on position 6 the resistor shunting switch R3 is closed to shunt the resistor 26 from the motor circuit. The energizing circuit for the switch R3 may be traced from the contact segment 73 on the controller AD through conductor 206 and the actuating coil of the switch R3 to negative.

It will be noted that the pilot controller may be rotated from position 6 to position 7 by the pilot motor when the master controller is moved to position 7 as the energizing circuit for the pilot motor is established through an interlock 207 on the relay 39. The energizing circuit for the pilot motor may be traced from the portion 145 of the segment 48 which is engaged by the finger 146 on the pilot controller, through conductors 147 and 148, the interlock 207 on the relay 39, conductor 126, contact members 87 on the relay HR, which is in its deenergized position at this time, and thence through a circuit previously traced to the pilot motor.

When the controllers are on position 7, the switch R4 is closed to shunt the resistor 29 from the motor circuit. The energizing circuit for the switch R4 extends from the segment 73 of the controller AD through conductor 208 and the actuating coil of the switch R4 to negative.

Also, on position 7 the switch LR1 is closed to shunt the resistor 27 from the motor circuit. The energizing circuit for the switch LR1 may be traced from the contact segment 72 through conductor 209 and the actuating coil of the switch LR1 to negative.

When the controllers are on position 8 the switch LR2 is closed to shunt the resistor 28 from the motor circuit. The energizing circuit

for the switch LR2 extends from the segment 72 to conductor 211 and the actuating coil of the switch LR2 to negative.

It will be noted that the closing of the switches LR1 and LR2 permits the switches R1, R2, R3 and R4 to be opened which makes the resistors 25, 26 and 27 available for reconnection in the motor circuit in parallel with the resistor 23 and the resistors 28, 29 and 30 available for reconnection in parallel with the resistor 24, thereby providing an additional number of accelerating steps without materially increasing the number of resistors and resistor shunting switches.

When the controllers are on position 9 the switches V1 and V2 are opened and the switch V3 is closed, thereby connecting the resistors 25, 26 and 27 in parallel with the resistor 23. The energizing circuit for the switch V3 may be traced from the segment 72 through conductor 212 and the actuating coil of the switch V3 to negative.

When the controllers are moved to position 10 the switch V4 is closed to connect the resistors 28, 29 and 30 in parallel with the resistor 24. The energizing circuit for the switch V4 extends from the segment 72 through conductor 213, and the actuating coil of the switch V4 to negative.

The circuits through the resistors may now be traced from the conductor 155 through conductor 168, the switch LS1, conductor 169, the resistors 25, 26 and 27, conductor 171, and the switch V3 to conductor 172, and also from conductor 155 through conductor 214, the switch LR1 and the resistor 23 to the conductor 172. Likewise, a circuit extends from the conductor 155 through conductor 168, the switch LS2, conductor 201, the resistors 30, 29 and 28, conductor 203 and the switch V4 to the conductor 172, and also from the conductor 155 through the conductor 214, the switch LR2 and the resistor 24 to the conductor 172.

The resistor shunting switches R1, R2, R3 and R4 are closed in the order shown in the sequence chart, Fig. 2, as the controllers are moved through positions 11, 12, 13 and 14, thereby shunting the resistors 25, 26, 29 and 30 from the motor circuit. When the controllers are moved to position 15 the switches V1 and V2 are reclosed to shunt the resistors 23 and 27, 24 and 28 from the motor circuit, thereby connecting the motors directly to the power source.

When the controllers are on position 16 the field shunting switches FS1, FS5 and FS9 are reclosed to shunt the motor fields, thereby causing the motors to operate at their maximum speed in a manner well known in the art.

As explained hereinbefore, the master controller may be moved toward its last position either step-by-step or in one operation. The pilot controller follows the movement of the master controller and is stopped on a position corresponding to that of the master controller. The controllers may be actuated toward their "off" positions in the same manner as when the locomotive is operating on alternating current, as described hereinbefore.

From the foregoing description it is apparent that I have provided a system which is suitable for controlling the operation of a locomotive or other electrically propelled vehicle when it is operating on either alternating current or direct current, and furthermore it is apparent that the system herein described is suitable for controlling two or more locomotives when operating in multiple. All of the locomotives during multiple op-

eration may be controlled from a single master controller located in the leading locomotive, and the motors in each locomotive will be operating at the same voltage and consequently at the same speed, since all of the pilot controllers will be in step with the master controller. The system herein described also provides protective features for insuring the correct operation of the control equipment.

10 Since many modifications may be made in the apparatus and arrangement of parts without departing from the spirit of my invention, I do not wish to be limited other than by the scope of the appended claims.

15 I claim as my invention:

1. In a locomotive control system, in combination, a motor, a power conductor, switching means for connecting the motor to the power conductor, a plurality of controllers for controlling the operation of said switching means, a pilot motor for driving said controllers at a predetermined speed, a master controller operable to a plurality of positions, a follow-up pilot controller, said pilot controller being driven by the pilot motor to a position corresponding to the position of the master controller, interlocking means on said switching means, and a relay energized through said interlocking means for stopping said pilot motor under predetermined conditions.

20 2. In a locomotive control system, in combination, a motor, a power transformer, a plurality of tap-changing switches for controlling the motor connections to said transformer, a plurality of controllers for controlling the operation of said switches, relay means energized by the power transformer and cooperating with said controllers in the control of said switches, a pilot motor for simultaneously driving said controllers at different rates of speed, and a manually operable master controller for controlling the operation of the pilot motor.

25 3. In a locomotive control system, in combination, a motor, a power transformer, a plurality of tap-changing switches for controlling the motor connections to said transformer, a plurality of controllers for controlling the operation of said switches, relay means energized by the power transformer and cooperating with said controllers in the control of said switches, a pilot motor for simultaneously driving said controllers at different rates of speed, a master controller manually operable to a plurality of positions, and a follow-up pilot controller driven by the pilot motor to a position corresponding to the position of the master controller and cooperating with the master controller in controlling the operation of the pilot motor.

30 4. In a locomotive control system, in combination, a motor, a power transformer, a plurality of main tap switches, a plurality of auxiliary tap switches cooperating with the main tap switches to vary the voltage applied to the motor from the transformer, a controller for controlling the operation of the main tap switches, an additional controller for controlling the operation of the auxiliary tap switches, a pilot motor for driving said controllers, a master controller, a pilot controller driven by the pilot motor and cooperating with the master controller in controlling the pilot motor, and interlocking means actuated by said main tap switches for also controlling the pilot motor.

35 5. In a locomotive control system, in combination, a motor, a power transformer, a plurality of main tap switches, a plurality of auxiliary tap

switches cooperating with the main tap switches to vary the voltage applied to the motor from the transformer, a controller for controlling the operation of the main tap switches, an additional controller for controlling the operation of the auxiliary tap switches, a pilot motor for driving said controllers, a master controller, a pilot controller driven by the pilot motor and cooperating with the master controller in controlling the pilot motor, and relay means responsive to the operation of said main tap switches for also controlling the pilot motor.

6. In a locomotive control system, in combination, a motor, means for connecting the motor to either an alternating or a direct current source of power, switching means for varying the voltage applied to the motor, a plurality of controllers for controlling the operation of said switching means, relay means energized by said power sources for also controlling the operation of said switching means, a pilot motor for driving said controllers, a master controller, and a pilot controller driven by said pilot motor and cooperating with the master controller in controlling the operation of the pilot motor.

7. In a locomotive control system, in combination, a motor, means for connecting the motor to either an alternating or a direct current source

5 of power, switching means for varying the voltage applied to the motor, a plurality of controllers for controlling the operation of said switching means, relay means energized by said power sources for also controlling the operation of said switching means, a pilot motor for driving said controllers at different rates of speed, a master controller operable to a plurality of positions, and a follow-up pilot controller driven by said pilot motor to a position corresponding to the position of the master controller.

10 15 20 25 8. In a locomotive control system, in combination, a motor, means for connecting the motor to either an alternating or a direct current source of power, a transformer for varying the motor voltage when operating on alternating current, a resistor for varying the motor voltage when operating on direct current, a plurality of switches for connecting to taps on the transformer, additional switches for shunting the resistor, controllers for controlling the operation of said switches, a pilot motor for driving said controllers, a master controller, and a pilot controller driven by said pilot motor and cooperating with the master controller in controlling the operation of the pilot motor.

LYNN G. RILEY.
